UNITED STATES PATENT OFFICE

113,551

DESIGN FOR A RANGE

Edwin R. Culver, Jr., St. Louis, Mo.

Application October 8, 1938, Serial No. 80,336

Term of patent 7 years

To all whom it may concern:

Be it known that I, Edwin R. Culver, Jr., a citizen of the United States, residing in the city of St. Louis and State of Missouri, have invented a new, original, and ornamental Design for Ranges, of which the following is a specification, reference being had therein to the accompanying drawing, forming part thereof.

In the drawing:

Figure 1 is a perspective view of the range embodying my new design; and

Figure 2 is a horizontal, sectional view taken substantially on the line 2—2 of Figure 1.

That end of the range not shown in the perspective view Fig. 1 is substantially plain.

The dominant features of my design reside in the portions shown in full lines.

I claim:

The ornamental design for a range, as shown and described.

EDWIN R. CULVER, JR.
